UNITED STATES PATENT OFFICE.

RALPH L. CROSTHWAITE, OF CHICAGO, ILLINOIS.

VENTILATOR AND THE LIKE.

Application filed July 18, 1925. Serial No. 44,523.

This invention relates to improvements in ventilators and the like, and more especially to ventilators and the like especially adapted for use with windows. The invention is particularly adapted for use in connection with ventilators and the like, such as, for example, screens, in connection with windows having sliding sashes.

The invention is here shown embodied in a device in which the ventilator consists of a panel provided with ventilating louvres. It is obvious, however, without detracting from the spirit of the invention, the ventilating member may be provided with screening, netting, webbing, or formed in any other manner in order to give the desired ventilation.

My improved ventilator is adapted to move upwardly and downwardly with the lower sash of the window as the same is opened and closed so that the opening will always be filled by the ventilator.

One of the features of my invention is the provision of means whereby the ventilator may be readily forced downwardly, if desired, into a well or pocket below the window-sill so that the entire window opening may be obtained without obstruction.

Another feature of the invention is the provision of means whereby, in the event the ventilator is pushed downwardly out of use, upon lowering the sash it will again automatically become attached to the same so that upon again raising the sash the ventilator will automatically move upwardly with it.

Another feature of my invention is the provision of means whereby after the ventilator has been moved upwardly to its highest position, it will automatically become detached from the window sash in the event it is desired to raise the sash higher. Upon lowering the sash the ventilator will again automatically become attached to the same and move downwardly and upwardly with it.

Other features and advantages of my invention will appear more fully as I proceed with my specification.

In that form of device embodying the features of my invention shown in the accompanying drawings, Figure 1 is a view in front elevation of my improved ventilator showing the same in use with a window having a sliding sash, Fig. 2 is a horizontal sectional view of one of the automatic catches used in connection with my device,

Fig. 3 is a view taken as indicated by the line 3—3 of Fig. 1, Fig. 4 is a view taken as indicated by the line 4—4 of Fig. 1.

As shown in the drawings 10 indicates the lower sliding sash of a window of usual construction adapted to slide in guides at the sides formed by the guide strips 11 and 12 in the usual manner. Below the window-sill 13 and in line with the guides in which the sash 10 slides is provided a well or pocket 14 in which is placed a pan 15.

16 indicates in general a ventilator adapted to slide upwardly and downwardly below the sash 10 in the same guides in which the sash slides. The ventilator 16 as here shown comprises a rectangular frame 17 provided with horizontally arranged overlapping slanting louvre slats 18 of the usual form. These louvre slats are arranged in order to permit the passage of air therebetween and at the same time exclude the rain. Obviously, any other kind of means may be provided for affecting the passage of air, such as, for example, screening and the like. The well 14 or chamber 14 and pan 15 are large enough to permit the entire ventilator 16 to slide downwardly into the well when the sash 10 is in its lowermost or closed position; so that in such case the window will be closed in the usual manner and the ventilator 16 entirely housed within the well or chamber 14.

The lower edge of the window sash 10 and the upper edge of the ventilator 16 are provided with cooperating parts of automatic catches so that normally the ventilator 16 will remain fastened to the sash and move upwardly and downwardly therewith. The catches are made, however, so that when the ventilator is in its uppermost position, as shown in Fig. 1, and it is desired to move the sash still higher said catches will automatically release. Upon again lowering the sash said catches will automatically engage when the sash comes into contact again with the ventilator. One of these catches is shown in detail in Fig. 2. It will be noted that the lower edge of the window sash 10 carries a downwardly projecting pin 19 provided with a slight annular grooved recess 20. The upper edge of the ventilator 16 is provided with a socket housing two horizontally slidable bolts 21. Each of these bolts is provided with a rounded head 22, and the same are normally urged toward each other by means of the spiral springs 23. The parts are so spaced and proportioned that the two heads 22, 22,

of the two bolts will yieldingly engage the annular recess 20 on the pin 19 and thus yieldingly hold the ventilator 16 attached to the sash 10. When the ventilator reaches the limit of its upward movement, further lifting of the sash will cause the pin 19 to be pulled out from between the heads 22, 22, of the bolts by separating the same slightly against the pressure of the springs 23, 23. When the 10 ventilator and sash are again brought into engagement, the head of the pin 19, which is rounded, will separate the bolts 21, 21 until they again snap back into engagement with the annular recess 20.

15 The ventilator 16 is suitably balanced by counterweights 24 in the same manner as the sash of a window. Any suitable means may be provided for limiting the upward movement of the ventilator. In a device as here 20 shown, such upward movement is limited by suitable placing of the pulley wheels 25 which carry the ropes 26 attached to the counterweights 24.

It is believed that the operation of the 25 device is clear. Normally, the ventilator 16 moves upwardly and downwardly with the sash 10. In Fig. 1 the ventilator is shown in substantially its uppermost position. If the sash is raised higher, the catches dis- 30 engage permitting the window to be raised as high as desired, the ventilator 16 remaining as it is. If desired, however, the ventilator may be pushed downwardly with the 35 hands completely into the well 14, so that the entire window opening may thus be obtained without any obstruction. Whenever the sash 10 is lowered, whether the ventilator is down in the well or not, as soon as the sash comes into engagement with the 40 ventilator, the catches will again automatically engage so that thereafter the ventilator will move upwardly and downwardly with the window within the limits of the movement of said ventilator.

45 While I have shown and described certain embodiments of my invention, it is understood that it is capable of many modifications. Changes, therefore, in the construction and arrangement may be made without departing from the spirit and scope of the invention as disclosed in the appended claims, in which it is my intention to claim all novelty inherent in my invention as broadly as possible in view of the prior art.

50 55 What I claim as new, and desire to secure by Letters Patent, is:

1. In combination with a window having

a sliding sash; a ventilator mounted in said window for vertical sliding movement below said sash; and means for detachably securing said ventilator to said sash, said securing means adapted to yieldingly hold the ventilator and sash in engagement, permit separation thereof under tension, and automatically engage upon the bringing of said sash and ventilator together.

2. In combination with a window having a sliding sash; a well below the sill of said window; a ventilator mounted in said window for vertical sliding movement below said sash, said ventilator adapted to slide down into said well and be completely housed therein; and means for detachably securing said ventilator to said sash, said securing means adapted to yieldingly hold the ventilator and sash in engagement, permit separation thereof under tension, and automatically engage upon the bringing of said sash and ventilator together.

3. In combination with a window having a sliding sash; a well below the sill of said window; a ventilator mounted in said window for vertical sliding movement below said sash, said ventilator adapted to slide down into said well and be completely housed therein; means for limiting the upward movement of said ventilator; and means for detachably securing said ventilator to said sash, said securing means adapted to yieldingly hold the ventilator and sash in engagement, permit separation thereof under tension, and automatically engage upon the bringing of said sash and ventilator together.

4. In combination with a window having a sliding sash; a well below the sill of said window; a ventilator mounted in said window for vertical sliding movement below said sash, said ventilator adapted to slide down into said well and be completely housed therein; means for limiting the upward movement of said ventilator beyond a position in which the ventilator is just substantially completely out of said well; and means for detachably securing said ventilator to said sash, said securing means adapted to yieldingly hold the ventilator and sash in engagement, permit separation thereof under tension, and automatically engage upon the bringing of said sash and ventilator together.

Witness my hand and seal this 16th day of July, A. D. 1925.

RALPH L. CROSTHWAITE. [L.S.]
